UNITED STATES PATENT OFFICE.

JOSEPH CURIN, OF CHICAGO, ILLINOIS.

DESIGN FOR A FACE PLATE.

Application filed February 16, 1928. Serial No. 25,458. Term of patent 3½ years.

To all whom it may concern:

Be it known that I, JOSEPH CURIN, a citizen of the United States, residing at Chicago, in the county of Cook and State of Illinois, have invented a new, original, and ornamental Design for Face Plates, of which the following is a specification, reference being had to the accompanying drawing, forming part thereof.

Fig. 1 is a front elevational view of a face plate showing my new design. Fig. 2 is a side elevation thereof.

I claim:

The ornamental design for a face plate, as shown.

JOSEPH CURIN.
